UNITED STATES PATENT OFFICE

160,650

DUST MOP

Julia Nigro, Kansas City, Mo.

Application February 20, 1950, Serial No. 8,030

Term of patent 14 years

(Cl. D9—2)

To all whom it may concern:

Be it known that I, Julia Nigro, a citizen of the United States, residing at Kansas City, in the county of Jackson and State of Missouri, have invented a new, original, and ornamental Design for a Dust Mop, of which the following is a specification, reference being had to the accompanying drawing, forming a part thereof.

Fig. 1 is a perspective view of a dust mop, showing my new design; and

Fig. 2 is an end elevational view thereof.

I claim:

The ornamental design for a dust mop, as shown.

JULIA NIGRO.
